UNITED STATES PATENT OFFICE.

MORRIS U. BERNHEIM, (NOW BY JUDICIAL CHANGE OF NAME MORRIS U. BURNHAM),
OF CINCINNATI, OHIO, ASSIGNOR TO THE ALVEY-FERGUSON COMPANY, OF OAK-
LEY, CINCINNATI, OHIO, A CORPORATION OF OHIO.

ROLLER FOR GRAVITY-CONVEYERS, &c.

1,373,047.

Specification of Letters Patent.

Patented Mar. 29, 1921.

Application filed June 10, 1918, Serial No. 239,143. Renewed September 22, 1919. Serial No. 325,522.

To all whom it may concern:

Be it known that I, MORRIS U. BERNHEIM, a citizen of the United States, residing at Cincinnati, in the county of Hamilton and 5 State of Ohio, have invented certain new and useful Improvements in Rollers for Gravity-Conveyers, &c., of which the following is a specification.

This invention relates to rollers and more 10 particularly to rollers of the type used in gravity conveyers, wherein the packages to be conveyed rest directly upon and are in almost constant contact with said rollers.

The object of the invention is to provide 15 a roller constructed in such manner that it will be markedly wear resistant, will not become battered out of shape by hard usage, will be in large measure noiseless in operation, will retain its alinement through a long 20 period of use and may be constructed at a very low cost.

In achievement of the foregoing objects I provide a roller comprising an outer metallic shell, a body portion formed of a suitable 25 non-metallic material, as wood, for example, arbors by which the roller may be mounted for rotation, end cups through which the arbors pass and means uniting the several parts in a simple and efficient way. The metallic 30 shell provides a wear resistant element which will give long life to the roller. The wooden body not only serves its function as a core to carry the arbors but the presence of this complete filling in the shells renders 35 the rollers less drum-like and consequently less noisy in operation while the metallic cups engage the arbors and support said arbors and prevent the openings in the ends of the wooden cores, into which the arbors 40 project, from becoming enlarged to such an extent as to cause the rollers to wobble, as has sometimes been the case with wooden rollers of ordinary construction.

Further objects and advantages of the invention will be set forth in the detailed description which now follows:

Referring to the drawings—

Figure 1 is a view, partly in longitudinal section and partly in elevation of a roller 50 constructed in accordance with the invention and wherein the metal shell extends the full length of the roller.

Fig. 2 is a like view illustrating a slightly different method of connecting the parts.

Fig. 3 is a like view of a structure comprising a wooden roller, part of which is exposed, but the portions whereof, adjacent the ends, are protected by metal caps. 55

Fig. 4 is a sectional view of one of the cups hereinbefore described and 60

Fig. 5 is a face view of said cup.

Like numerals designate corresponding parts in all of the figures of the drawings.

Referring to the drawings and particularly to Fig. 1, 5 designates a hard wood 65 core or body portion that is surrounded by a steel shell 6. This steel shell extends outwardly beyond each end of the core 5 a sufficient distance to form a recess within which cup shaped members 7 are received. 70 These cup shaped members are preferably provided with inturned flanges 8 which define central openings formed in said members. Stub shafts or axles 9 project through these openings and enter openings 10 formed 75 in the opposite ends of the core 5. The axles or stub shafts 9 are serrated as indicated at 11 and these serrated portions receive the correspondingly shaped ends 12 of dowels 13, said dowels passing 80 through the shell 6, through the core 5 and engaging the serrated portions 11 of the shafts as stated. The heads of the dowels 13 are flared as indicated at 13^a and are countersunk in the shell. 85

In assembling the construction illustrated in Fig. 1, the core 5 is first driven into the steel shell. The cup-like members 7 are then driven into the open ends of the shell until they abut against the ends of the core 5, 90 after which the shell is spun over as indicated at 14 to thereby secure the cup like members firmly in place and to hold the core 5 against endwise movement with respect to the shell 6. The stub shafts or 95 axles 7 are then driven into place and in order to aid in securing the shafts in position the openings defined by the flanges 8 are made slightly smaller in diameter than the shafts, so that the material of the 100 flanges must spring as the shafts are driven into position. After the shafts are in place the dowels 13 are put into place as hereinbefore set forth.

In the construction illustrated in Fig. 2 105 the steel shell 6^a is substantially equal in length, to the core, and the ends of the core are slightly reduced as indicated at 15 to

permit cup-like members 16 to be driven upon said reduced ends. The stub shafts 17 are like the stub shafts 7 and are serrated at 11, as in the former case. In this construction dowels 13^b traverse the steel shell, the cup-like members 16, and those portions of the core which project into said cup-like members. The inner ends of these dowels are serrated at 12^a to adapt them to engage with the serrations 11. The cup-like members 16 are provided with plain openings 18 through which the stub shafts 17 pass, said shafts entering openings 10^a of the body portion or core 5^a of the roller.

15 The presence of the steel shells in the above described construction renders the rollers wear resisting to a marked degree, while the fact that the interiors of these steel shells are completely filled, deaden the noise which would otherwise be created by the use of hollow, metallic rollers.

In the form of the invention illustrated in Fig. 3, I have illustrated a wooden roller 20, the central portion of which is concaved 25 as indicated at 21. In rollers of this type, packages being conveyed are supported upon the shoulder 22, at the opposite ends of the rollers. When rollers of this type are to be employed, cup-like caps 23 are driven 30 upon the opposite ends of the rollers, said rollers being reduced in diameter at 24, to such an extent as to leave the outer surfaces of the caps flush with the shoulders 22. The caps 23 are provided with central openings 25 and the roller is provided with openings 26 in alinement with the openings 25 of the caps, which openings serve to receive stub shafts or axles like those described with respect to Fig. 1 and to which 40 the same reference characters have been applied. In this construction dowels 27 traverse the caps 23 and those portions of the roller 22 which lie within said caps and the inner ends of these dowels engage the serrated portions 11 of the shaft or axle. It will be noted that the serrated portions upon the shafts are adapted to be engaged by the dowels at a plurality of points upon the surface of the shafts, both longitudinally and 50 circumferentially. This renders it unnecessary to accurately aline any exact spot upon or part of the shaft with the inner end of the dowel.

It will be understood that these shafts or 55 axles serve to mount the rollers in conveyer frames 28 which are usually, though not necessarily, of angle iron.

While the invention is primarily intended for use in connection with the rollers of 60 gravity conveyers, it is apparent that rollers constructed in accordance therewith may be used in many other relations, such for example as idlers or guide rollers for belt conveyers, those features which lend rigidity,

strength, long life and freedom from noise 65 being manifestly of value in the relation indicated as well as in conjunction with gravity conveyers.

While the several constructions shown and described provide rollers having the advantages recited, it is to be understood that the constructions illustrated in the drawings are merely exemplary and that the principles involved form the real gist of the invention irrespective of the particular mechanical form in which they may be embodied. It is therefore to be understood that the invention is not limited to the precise construction set forth, but that it includes within its purview whatever changes so fairly come within the spirit of the appended claims.

Having described my invention what I claim is:

1. A roller comprising a non-metallic body portion, a metallic housing covering the end and embracing the periphery of the body portion, a shaft supported partly in the housing and partly in the body portion and means traversing the body portion and having an end adapted to engage the shaft at a plurality of points upon its surface and to hold the shaft against endwise movement.

2. A roller comprising a non-metallic body portion, a shell incasing the same, a metallic annulus inserted in the end of said shell, an axle supported partly in the body portion and partly in said shell, and means traversing said shell and the body portion and engaging said shell.

3. A roller comprising a non-metallic body portion, a shell incasing the same, a metallic annulus inserted in the end of said shell, an axle supported partly in the body portion and partly in said shell, and means traversing said shell and the body portion.

4. A roller comprising a non-metallic body portion, a shell incasing the same, a metallic annulus inserted in the end of said shell, an axle supported partly in the body portion and partly in said shell, and means traversing said shell, and annulus and the body portion and engaging said shaft.

5. A device of the character described comprising a non-metallic body portion a 115 metallic element at the end thereof having an opening formed therethrough, a shaft supported partly in said element and partly in the body portion and having an indented part lying within said body portion and a 120 dowel traversing the body portion, and having an end shaped to enter the indented portion of the shaft.

6. A roller of the character described, comprising a solid non-metallic body portion, a metallic shell embracing the same and projecting beyond the ends thereof, and an annulus of cup-like formation seated in

the projecting portion of the shell and bearing against the end of the body portion, the end of the shell being bent inwardly to engage said annulus and bind the same in position.

7. A roller of the character described, comprising a solid non-metallic body portion, a metallic shell embracing the same and projecting beyond the ends thereof, and an annulus of cup-like formation seated in the projecting portion of the shell and bearing against the end of the body portion, the end of the shell being bent inwardly to engage said annulus and bind the same in position, and a shaft projecting through said annulus and into the body portion.

8. A roller of the character described, comprising a solid non-metallic body portion, a metallic shell embracing the same and projecting beyond the ends thereof, and an annulus of cup-like formation seated in the projecting portion of the shell and bearing against the end of the body portion, the end of the shell being bent inwardly to engage said annulus and bind the same in position; and a shaft projecting through said annulus and into the body portion, said shaft being provided in its length with indented portions, and means traversing the shell and the body portion and engaging the indented portions of the shaft.

9. A roller of the character described, comprising a non-metallic, solid body portion, a metallic shell embracing the same and projecting beyond the end thereof, an annulus of cup-like formation seated in the projecting portion of the shell and having an opening surrounded by a flange, and a shaft of slightly larger diameter than said opening, which shaft is forced through the opening and enters the body portion.

10. A roller of the character described, comprising a non-metallic, solid body portion, a metallic shell embracing the same and projecting beyond the end thereof, an annulus of cup-like formation seated in the projecting portion of the shell and having an opening surrounded by a flange, a shaft of slightly larger diameter than said opening, which shaft is forced through the opening and enters the body portion, and means traversing the shell and the body portion and engaging said shaft to prevent endwise movement of the shaft with respect to the body portion.

11. A roller of the character described,

comprising a non-metallic, solid body portion, a metallic shell embracing the same and projecting beyond the end thereof, an annulus of cup-like formation seated in the projecting portion of the shell and having an opening surrounded by a flange, a shaft of slightly larger diameter than said opening, which shaft is forced through the opening and enters the body portion, dowels traversing the shell and the body portion, said dowels having pointed inner ends and serrated portions formed upon the shaft with which the inner ends of the dowels are adapted to engage.

12. A roller of the character described, comprising a solid, non-metallic body portion, a shell of metal embracing the same, a cup-like annulus located at each end of the body portion and embracing the end of said body portion and lying inwardly of said shell, each end of the roller being provided with a longitudinally extending opening which alines with a corresponding opening formed in the adjacent annular member, shafts located in said openings and members traversing the shell, the annular members and the body portion and engaging said shafts to prevent endwise movement of the shaft with respect to said body portion.

13. A roller of the character described, comprising a non-metallic body portion, an annular member at each end thereof which engages over a reduced part of the end portions of said roller, a metallic shell embracing said annular member and the body portion of the roller, shafts supported jointly in said annular members and in the body portion and dowel pins traversing said shell, said annular members and the body portion and being provided with pointed inner ends adapted to engage with the shaft.

14. A roller of the character described, comprising a non-metallic body portion having its opposed ends reduced, cup-like caps upon said reduced ends the outer surfaces of which lie flush with the adjacent portions of the roller, shafts supported jointly in the cup-like caps and in the body portion of the roller and means traversing said cup-like caps and the body portion of the roller and having ends adapted to engage the shafts at a plurality of points both circumferentially and longitudinally to hold the same against endwise movement.

In testimony whereof I affix my signature.
MORRIS U. BERNHEIM.
